LOT OR BUNDLE ASSORTER FOR IRONING
MACHINES

Forrest J. Couch, Rochester, N. Y., assignor to
The American Laundry Machinery Company,
Cincinnati, Ohio, a corporation of Ohio

Original application November 3, 1930, Serial No.
493,050. Divided and this application April 5,
1933, Serial No. 664,581

4 Claims. (Cl. 198—158)

My invention relates to a lot or bundle assorter for ironing machines and, particularly, to a lot or bundle assorter for ironing machines or the like where the goods are ironed automatically and continuously delivered to a certain point.

This application is a division of application Serial No. 493,050, filed November 3, 1930, and which resulted in Patent No. 1,928,348, granted September 26, 1933.

10 The invention is especially applicable to ironing machines and is particularly advantageous where the family bundle service ironing is employed and wherein it is desirable to keep each family bundle of goods separated from others, 15 to have each family bundle of goods placed in a different receptacle or compartment, and to eliminate the labor necessary to remove filled receptacles from the point of delivery and substitute empty receptacles therefor manually. My invention 20 contemplates the provision of a conveying mechanism embodying an endless chain carrying a series of compartments and having operating mechanism so controlled and synchronized that each separate compartment carried by the chain 25 will automatically be moved to a point of delivery and will remain stationary at the point of delivery a sufficient length of time to collect one family's bundle or lot of goods.

The objects of my invention are to provide a 30 means for keeping each customer's lot of goods separated from others; to provide an endless row of compartments so arranged that each customer's lot of goods may be delivered in a single compartment; and to provide an operating mechanism such that each compartment may be 35 stopped at the delivery point a sufficient length of time to receive all of one customer's goods and may then be moved onwardly and another compartment brought into registry with the delivery 40 point, the operating apparatus being such that the compartments may be stopped or moved, as required.

Various other objects and advantageous features of my invention may be seen in the following 45 description and one embodiment thereof may be seen in the accompanying drawings wherein similar characters of reference designate corresponding parts, and wherein:

Fig. 1 is a side elevation of a delivery conveyor constructed in accordance with my invention; Fig. 2 is a plan view of the delivery conveyor shown in Fig. 1; Fig. 3 is a side elevation of the operating means for the delivery conveyor shown in Fig. 1 but without the parts 50 thereof in operative connection; and Fig. 4 is

a perspective view of the relatively thick pad used for mechanism tripping purposes.

Referring to the drawings, an ironing roll 1 is shown in cooperative relation with an ironing chest 2, the roll and chest being of the usual type found in a flat work machine. Also, as is usual in ironing machines, a tape 3 passes around the ironing roll and between the roll and chest.

In accordance with my invention, a bracket 4 is rigidly secured to each side of the rearwardmost end of the chest 2 and each bracket is provided with an upwardly extending ear 5 to which an arm 6 is pivoted as at 7. This arm carries the usual stripper roller 8 intermediate its ends and closer to its outermost end, the stripper roller being mounted on a shaft 9 journaled in the arms, and a roller 10 intermediate the stripper roller 8 and the pivot point 7. One end of the roller rests on or near the rear end of the chest 2 by gravity and the other end is held 20 downwardly by means of a sprocket chain 11 traveling around a sprocket 12 on the shaft 13 which carries the roller 10 and driven sprocket 14 which causes rotation of the roller 10. With this construction, the ironed goods passes under 25 the roller 10 and then falls away from the rearwardmost end of the chest 2 or, if necessary, is stripped from the tape 3 by the stripper roller 8.

A conveyor mechanism and operating means 30 therefor, is mounted on a frame 15 and disposed adjacent the delivery end of the chest 2 and comprises an endless conveyor chain 16 that may be of chain or otherwise that travels about a driven sprocket 17, over an idler sprocket 18 and around 35 an idler sprocket 19, returning back to and around the driven sprocket 17. One end of the endless conveyor 16 is disposed directly below the roller 10 whereby all goods delivered from the ironing machine will fall directly on the conveyor 40 and the position of the conveyor between the idler sprockets 18 and 19 is substantially horizontal while the remainder of the conveyor is disposed at an angle to the horizontal. The horizontal position of the conveyor is supported at a 45 convenient height by means of suitable guides which may be of angle iron and the conveyor may extend horizontally away from the ironing machine as far as is desired.

In itself, the conveyor of which the chain 16 50 forms a part consists of a plurality of compartments separated by vertical partitions 21. Also, in viewing the horizontal position of the conveyor, the bottom of each compartment formed by the vertical partitions 21 consists of several 55

substantially rectangularly shaped plates 22 each having one edge pivotally connected to the endless chain 16. Each vertical partition 21 is preferably made integral with the plate 22 which is adjacent thereto and there is a substantially greater number of plates 22 than partitions 21 whereby a number of compartments may be formed throughout the length of the conveyor. However, it will be understood that the number of compartments or the size thereof may be varied by different spacings of the plates 22 carrying the partitions 21.

The apparatus is so constructed and the travel of the conveyor is in such direction about the driven and idler sprockets that the plates 22 will lie in a position of overlapping relation in the same general longitudinal line as the conveyor chain along that portion of the chain that is above the driven and idler sprockets. It follows that, since the plates 22 are pivoted on the conveyor chain, the plates will tend to swing to a substantially vertical position with the partitions 21 disposed substantially horizontally when the portion of the conveyor above the driven and idler sprockets travels therearound to a position beneath the sprockets or, in other words, reaches the return lap, the plates and partitions tending to swing to their respective positions just mentioned by force of gravity. Supporting tracks 23 are provided along which the free edges of the plates slide during the return lap of the conveyor and such tracks diverge outwardly from the conveyor chain 16 as it approaches a position below the shaft 24 on which the driven sprocket 17 is mounted whereby the free edges of the plates 22 and the partitions 21 are entirely free from the tracks so that they may follow the chain 16 around the sprocket 17 without binding. At the remote idlers 19, the tracks 20 are curved as at 25 so that the extremities of the track extend above the idlers 19 to prevent any noise being caused by the falling of the free edge of each plate 22 or partition 21 as the center of gravity passes the vertical plane of the center of the idlers 19. In Fig. 2, it will be noted that the partitions 21 are cut back as at 21' to be shorter than the plates 22 whereby they will move freely between the tracks 23 while the ends of the plates 22 from which the partitions extend ride on the tracks.

With this arrangement, when a plate 22 with its partition 21 reaches the point where it is just beginning to move around the sprocket 19, the ends of the plates engage the lower side of the curved portions 25 of the tracks while the partitions 21 pass between the tracks. The curvature 25 of the tracks is so developed that the tracks do not bind the plates 22 at any point in their movement around the sprocket 19 but allow the plates to follow naturally around with the exception that their outer edge is held back. As shown, the tracks 23 below the conveyor are so arranged as to permit the plates 22 to gradually swing toward normal depending position along the under lap of the conveyor as they approach the drive sprocket 17 and to entirely release the plates just prior to or as they begin to move around such drive sprocket toward the upper lap of the conveyor. Of course, the plates 22 having no partition members 21 thereon follow a similar path.

The size of the sprocket wheels 17 mounted on the shaft 24 about which the endless chains 16 pass is such that one revolution of the sprockets will cause the conveyor mechanism of which the chains form a part to travel a distance equal to

the distance from one partition to another. It follows, therefore, that the size of the sprockets 17 must be changed when the size of the compartments is changed by varying the distance between the partitions 21 in order to obtain the proper synchronism of movement of the compartments. The partitions 21 are all equally spaced apart and the size of the sprocket 17 is such that a compartment formed between two partitions will always be positioned directly below the rear edge of the chest 2 each time the conveyor comes to a stop.

In order to control the operation of the conveyor, a trip 26 is provided that takes the form of a bell crank lever having a long and a short arm, the trip being pivotally mounted as at 27 on a disk 28 which is rigidly mounted on the shaft 24. Loosely mounted on the shaft 24 a short distance from the disk 28 is another disk 29 which is provided with four pins or lugs 30 projecting from its face towards the disk 28 and into the same vertical plane as the short arm of the trip 26 occupies. The trip 26 is limited in its movement about the pivot 27 in one direction by a stop pin 31 and in the other direction by a stop pin 32. A spring 33 normally tends to hold the trip 26 in a position with the long arm thereof against the stop 32 and with the short arm of the trip in a raised position whereby it will be in the arcuate path of travel of the pins 30.

The disk 29 is constantly rotated or driven clockwise as will be hereinafter described and, being loosely mounted on the shaft 24, with the trip 26 on the disk 28 which is rigidly mounted on the shaft 24 in such position that the short arm thereof will not contact with any of the pins, the shaft 24 and sprockets 17 will not be rotated and the conveyor will remain stationary.

To provide a means for moving the trip 26 to such position that the short arm thereof will be raised into the path of travel of the pins 30, an arm 34 is pivotally mounted on the frame of the conveyor as at 35 and has its free end arranged to be in either of two positions, namely, in the path of the long arm of the trip 26 as shown in Fig. 1 wherein the short arm of the trip will be moved out of the path of travel of the pins 30 and the trip held against the stop 31, or out of the path of the long arm of the trip 26, see Fig. 3, and in such position that the trip will be moved against the stop 32 by spring 33, which movement will cause the short arm of the trip to be moved upward into the path of travel of the pins 30. As is clearly shown in the drawings, the free end of the arm 34 is made to swing in a vertical plane out of and into the path of the trip 26 which moves with the disk 28. The free end of the arm 34 is connected by a link 36 to the free extending end of one of the arms 6 mounted on the bracket 4 as hereinbefore described whereby when such arm 6 is raised the arm 34 will be raised and the free end lifted out of the path of the long arm of the trip 26 to permit the trip to be swung to the position hereinbefore described by means of the spring 33 and thereby bring the short arm of the trip into the circular path of the pins 30.

The disk 29 is constantly rotated in a clockwise direction which will move the upper lap of the conveyor to the right as shown in Fig. 1 and the lower end thereof to the left so that the partitions 21 will be brought to vertical position immediately under the delivery end of the ironing machine and the plates 22 will gravitate into

the overlapping position shown in Fig. 1 on the upper lap of the conveyor. Such disk 29 is constantly rotated by means of a gear wheel 31 integral with the disk and meshing with a gear 5 38 integral with a sprocket 39 which is connected by means of a chain 40 to a constantly rotating sprocket 41 of the ironing machine and provided with a chain tightener consisting of an arm 42, roller 43, and spring 44. It will be 10 understood that, if desired, a separate motor may be employed for constantly rotating the disk 29.

As a safety device, or to provide a means for starting travel of the conveyor at any time, a lifting button 45 is provided at a convenient 15 location which is connected to the arm 34 by means of a link 46, the connection to the arm 34 being on such side of the pivot that raising of the button 45 will move the free end of the arm 34 upwardly and disengage the free end 20 thereof from the long arm of the trip 26 whereby the short arm of the trip will move into the path of travel of the pins 30.

In the operation of this device, the ironed goods fall from the delivery end of the steam 25 chest into the compartment of the conveyor which is at rest directly below such delivery point and when the last piece of a customer's goods has been fed into the feed end of the ironing machine the operator follows it immediately 30 with a relatively thick pad A which passes through the ironer and under the roll 10 whereby such roller will be lifted slightly to cause the extended free end of the lever 9 to which the link 36 is connected to be moved upwardly about 35 the pivot 1 a sufficient distance to release the trip 26 by moving the arm 34 upwardly and out of engagement therewith whereby the short arm of the trip will move into the path of travel of the pins 30 as hereinbefore described. This will 40 cause one complete revolution of the sprockets 17 around which the conveyor passes and movement of the filled compartment out of registry with the delivery point and the next adjacent empty compartment into registry therewith. 45 Goods may be removed from the compartments when they reach the horizontal position shown in Fig. 1. The thick pad is of such width that it will pass entirely out from under the ironing machine roll 10 whereby the arm 34 may again 50 drop downwardly into a position to engage the long arm of the trip 26 prior to the disk 28 making one complete revolution whereby the long end of the trip will engage the free end of the arm 34 and the short arm of the trip moved 55 out of the path of the pins 30 as hereinbefore described. To guard against any pieces of goods falling to either side of the conveyor when they fall by gravity from the delivery end of the chest 2, substantially vertical side pieces 47 are secured to the conveyor frame on each side of the conveyor.

Referring to the drawings and the preceding description, it will be seen that I have provided an apparatus of the above type embodying numerous novel and advantageous features. For 60

instance, I have provided a delivery conveyor wherein bundles of clothes that are maintained in separated relation from other bundles during previous laundry operations may be ironed and collected in separate compartments and thus be maintained in their respective bundles whereby the necessity of again separating the clothes after the ironing operation is done away with. Another feature resides in the fact that the conveyor is so constructed as to present successive 10 empty compartments at the delivery point of the ironing machine and removing filled compartments automatically and without the use of manual labor. Various other features will be readily apparent.

What I claim is:

1. A conveyor, comprising an endless belt having pivoted plate members thereon arranged to form a conveyor bottom for the upper lap of the belt but not for the return lap thereof, some of 20 said pivoted plate members being angular in form to provide compartment forming partitions, and other of said plate members being solely bottom-forming members.

2. A conveyor, comprising a conveying element 25 having a plurality of compartments thereon, said compartments including pivoted plates adapted to lie in overlapping relation on the upper lap of said conveying element to form a bottom and to depend from their pivots on the return lap thereof, some of 30 said plates being angular to provide compartment partition members when on the upper lap of the conveyor element, and other of said plates being flat bottom-forming members.

3. A conveyor comprising an endless belt having a plurality of compartments thereon, said compartments including pivoted plates adapted to lie in overlapping relation on the upper lap of said belt to form a bottom and to depend from 35 their pivots on the return lap thereof, certain 40 of said plates being flat to form bottom members for the compartments and other of said plates being angular to provide partition members for said compartments, and said plates being assembled along said belt with a plurality of said 45 flat plates between consecutive angular plates.

4. A conveyor, comprising an endless belt including a plurality of pivoted plate members arranged to lie parallel with the upper lap of the belt to form a work receiving surface and tending to assume a position perpendicular to the return lap of the belt along such return lap, rollers about which said belt travels, some of 50 said plate members being angular to provide compartment forming partitions, others of said 55 plate members being solely bottom-forming members, and spaced track members arranged to engage the ends of said plate members at a point along the conveyor adjacent the beginning of plate movement from parallel position and guide 60 said plate position along the conveyor return lap, said angular portions of said plate members being cut away at their ends so as to pass between said track members.

FORREST J. COUCH. 65
